GRAPPLE

Filed April 22, 1942

UNITED STATES PATENT OFFICE

2,329,554

GRAPPLE

Leonard C. Pietsch, Gary, Ind., assignor to Inland Steel Company, Chicago, Ill., a corporation of Delaware

Application April 22, 1942, Serial No. 439,996

3 Claims. (Cl. 294—101)

My invention relates to grapples for use more particularly in the moving of relatively heavy objects from one position to another, as for example, and more especially, the hinged ends of gondola cars.

In connection with the use of my invention as applied to the hinged ends of gondola cars, it may be stated that it is the common practice of railroads to deliver such cars in empty condition, with the car ends swung down onto the floors of the cars, requiring that the one receiving the cars swing the car ends, which are heavy, into vertical position to close the cars preliminary to loading, this operation in accordance with previous practice being a source of trouble and injury to the workmen.

One of my objects is to provide a construction of grapple whereby the operation of moving an object, particularly the swinging of a hinged car end to closed position, may be effected without danger to the workmen.

Another object is to provide a simple and economical construction of grapple which will be of relatively light weight and be positive in its action.

Another object is to provide a construction of grapple which may be used with objects of different thickness and of different materials.

Another object is to provide a highly effective construction of grapple which may be readily manually manipulated to release it from the object.

Another object is to provide a construction of grapple by which a car end may be swung to closed position without requiring the prying of the car end by a bar thereby avoiding injury to the workmen from slippage of the bar; and other objects as will be manifest from the following description.

Referring to the accompanying drawing:

Figure 1 is a view in longitudinal sectional elevation of one end of a gondola car showing my improved grapple applied to the hinged car end for swinging it to the raised position shown by dotted lines.

Figure 2 is a fragmentary sectional view taken at the irregular line 2—2 on Fig. 1 and viewed in the direction of the arrows; and

Figure 3 a similar view taken at the line 3 on Fig. 1 and viewed in the direction of the arrow.

Referring to the particular illustrated construction of grapple it comprises a member 4 shown as of yoke form one of the legs of which, represented at 5 and shown as straight, being provided in the form of an inwardly extending

hook 6 with its terminal end of wedge shape as shown at 7 and the other leg represented at 8 being bifurcated as represented at 9.

The grapple also comprises a lever 10 having diverging end portions 11 and 12, and an intermediate portion presenting an arcuate laterally extending cam 14.

The lever 10 is located in the bifurcated portion 9 of the member and is pivoted therein by a pivot pin 15 positioned in the outer end of the leg 8 of the yoke member 4 and in the lever 10 at the juncture of the diverging portions 11 and 12 of the lever 10, the pin 15 being so positioned that the cam surface 14 of the lever 10 is disposed eccentric of this pin.

Referring now to the construction of the car structure shown and to which, by way of example, my improved grapple is illustrated as applied to raise the car end, it comprises, in accordance with a well known design, a floor 16, longitudinal side walls, one of which is shown at 17, and hinged end-walls one being shown at 18, the car shown being of a type formed of metal wherein the hinged car ends 18 are each formed of a frame having upper and lower sills 19 and 20, respectively, and a panel portion 21 filling the same.

The car ends are hinged to the floor 16 to swing from the open position (shown by full lines in Fig. 1) to the closed, substantially vertical, position shown by dotted lines in this figure, the hinging means shown and provided for each car end and representative of a common construction comprising a plurality of strap-loops (one of which is shown at 22) secured at intervals to the bottom sill 20 and U-bolts (one of which is shown at 23) carried by the floor 16 and looped through the strap-loops 22, sufficient play of the U-bolts being provided for to permit the car ends to swing into and out of closed position without obstruction. The location of the strap loops 22 is such as shown, and which is common practice, that the axis about which the car end swings is disposed inwardly of the face of the car end considering the latter as in closed position as shown by dotted lines in Fig. 1 and thus the car end is moved at the end of its closing movement, by gravity to its final closed position in which it becomes latched in place in accordance with common practice.

In the use of the grapple its hook end is inserted between the sill 19, near its center, and the floor 16 of the car, to the position shown by full lines in Fig. 1, the yoke member 4 being struck a slight hammer blow or other pressure

applied, if necessary, to position the grapple as stated, in which position of the parts the edge portion of the car end is straddled by the yoke member 4, and the hook 6 extends inwardly of the inner edge of the sill 19.

In practice the grapple would be associated with hoisting means, such as for example a crane or block and tackle mechanism, to the hook of which, shown at 24, the outer end of the arm 12 of the lever 10 would be connected, as for example, by a cable 25 looped over the hook 24 and through a clevis 26 pivoted to the lever 10.

The lifting action of the hoisting means swings the lever 10 counterclockwise in Fig. 1 thereby rotating the cam 14 against the car end and clamping the latter between the cam and the leg 5 of member 4 thus securely locking the grapple to the car end.

After the grapple has been lifted about 12" to 18" the hoisting mechanism would be moved to the left in Fig. 1, while continuing to be raised, for swinging the car end to closed position.

As will be noted, the grapple once applied to the car end is held in place thereon throughout the movement of the car end to closed position, the hook 6 preventing the grapple from slipping off the car end, thereby freeing the workmen of danger from injury as after pressure is applied by the hoisting mechanism to the grapple there is no need of a workman holding or guiding the car end to closed position.

In this connection it may be stated that the lever-arm 11 is preferably of such weight that at least during the final portion of the movement of the grapple for moving the car end to closed position it will continue to force the cam 14 toward the hook 6 and prevent premature release of the grapple from the car end even during the releasing of pressure applied to the lever 10 by the hoisting means, as for example in the final gravity-closing movement of the car end, the grapple being readily released by the workman by swinging the lever 10 in clockwise direction.

It is desirable that means be provided for normally holding the lever 10 and yoke member 4 from swinging on each other when the grapple is not in use and while being moved from one location to another, particularly to avoid injury to the workmen, a desirable form of means for this purpose being a pin not shown which may be inserted into holes in the lever 10 and member 4 which register with each other in one position of these parts. Preferably these holes represented at 27 and 28 are so disposed as shown that they register with each other when the grapple is in open position not only serving when the pin is inserted into these holes, to hold the parts from swinging one on the other but also facilitating the application of the grapple to an object to be shifted.

The grapple while shown as used with a car end of metal may be used equally well with a car end made of wood, as the pressure applied by the cam 14 will cause the nose 6 of the hook to gouge into the wood and afford the same position coupling action as in the case of its use on a metal car end.

While I have illustrated and described a particular construction embodying my invention I do not wish to be understood as intending to limit it thereto as the same may be variously modified and altered and the invention embodied in other forms of structure without departing from the spirit of my invention.

What I claim as new and desire to secure by Letters Patent is:

1. A grapple by which to swing an object from a substantially horizontal position to a substantially vertical position comprising a pair of members to straddle the object to be moved, one of said members being a lever pivoted between its ends to the other of said members and having a cam portion which, when said lever is swung in one direction, moves toward the object to connect the grapple at the cam portion and at the other of said members with the object, said cam portion when said lever is swung in the opposite direction moving away from the object to release the object, said lever having an arm which in the substantially horizontal straddling position of the grapple on an object inclines upwardly from said pivot at the side thereof at which said cam portion is located and exerts force tending to force said cam portion against the object in said last referred to position of the grapple and throughout the movement of the grapple to substantially vertical straddling position.

2. A grapple for use in shifting an article from horizontal to upright position comprising an angle member formed with an article-engaging arm and a lever-carrying arm at substantially right angles and with the extremity of the latter arm deflected to overhang the space included in the angle; an integral cam and lever member pivoted to said angle member adjacent said extremity and comprising a cam portion projecting from the pivot toward the article engaging arm, a clamping lever extending from said pivot toward said lever-carrying arm and a release lever extending from said pivot away from said lever-carrying arm; and a lip projecting from said article-engaging arm to engage an edge portion of the article to prevent premature disengagement.

3. The combination of claim 2 with said lever carrying arm and said clamping lever formed with openings in positions to register in open position of the grapple for reception of a locking pin.
